SHIFT KEY MECHANISM FOR ACCORDIONS

Max B. Luttbeg, St. Louis, Mo.

Application August 12, 1935, Serial No. 35,770

12 Claims. (Cl. 84—376)

This invention relates generally to accordions and more particularly to shift key mechanism for changing or varying the tone effects of the accordion.

5 The better class of accordions is generally equipped with means for shutting off certain groups of reeds of the treble section, thereby producing various tone effects. Thus in an accordion, the treble section of which has four 10 reed trays or blocks, the following tonal changes can be produced by using two shift keys to close certain of said reed blocks:

- (1) Flute oboe,
- (2) English horn bandonion,
- 15 (3) Violin effect,
- (4) Natural accordion tone, low octave.

Heretofore, such an accordion had the shift keys arranged generally on the edge of the keyboard at right angle to the keys or on the rear side thereof and they were operated by the palm 20 of the player's right hand which had to be moved from its regular position on the keyboard and the pressure had to be on the back part of the strip or shift key so as to force it rearwardly in order to operate the shifting mechanism which is 25 mounted on the back of the keyboard. This proved very inconvenient as it interfered with the regular playing movements of the player and caused strain on the hand due to the unnatural 30 position thereof as the arm had to be held close to the body. The shift keys were arranged longitudinally of each other due to the narrowness 35 of the keyboard. Furthermore, the shift keys were so located that they easily caught on the coat or sleeve of the player or accidentally became actuated when the accordion was held close to the body of the player.

One of the objects of the present invention is 40 to provide an accordion in which the shift keys are located on the front of the accordion adjacent to and substantially in the same plane with the keys of the treble keyboard so that such shift keys can be actuated by the tips of the fingers without requiring the player's hand to be moved from its regular playing position.

45 Another object of the invention is so to arrange the shift keys that they can be easily operated during the playing operation to change the playing tone of the accordion from a lower octave to a higher octave, and vice versa, thereby enlarging the playing scope of the accordion.

Other objects of the invention are to provide 50 novel means for operating the reed tray valves or slide plates with the shift keys positioned forwardly of and substantially in the same plane

with the keys of the treble keyboard so that said shift keys can be operated with the same ease and in the same manner as the keys of said keyboard.

Still other objects of the invention are to provide 5 novel and efficient means for sealing the operating connection between the shift key mechanism and the reed section so as to prevent leakage of air from the latter.

With these and other objects in view, my invention consists in certain novel features of construction and arrangement of parts, hereinafter more fully described and claimed, and illustrated in the accompanying drawings, in which—

Figure 1 is a front elevational view of my improved 15 accordion.

Figure 2 is a full-sized detail view of the shift key mechanism with the keyboard partly broken away.

Figure 3 is a top plan view of the treble reed 20 section with the reed trays partly broken away.

Figure 4 is an enlarged cross section taken on line 4—4 of Figure 3.

Figure 5 is an enlarged fragmental cross section taken on line 5—5 of Figure 1.

Figure 6 is a fragmental front elevational view 25 of the part shown in Figure 5.

Figure 7 is a horizontal cross section taken on line 7—7 of Figure 2.

Figure 8 is an enlarged fragmental cross section 30 of one of the reed trays and the slide plate therefor.

Figure 9 is an enlarged detail view of the indicator.

Figure 10 is a side elevational view of same.

Figure 11 is an elevational view of another 35 form of shift mechanism attached to the treble section.

Figure 12 is a side elevational view of same with parts of the accordion broken away.

Figure 13 is an enlarged transverse cross section taken on line 13—13 of Figure 11.

Figure 14 is an enlarged cross section through 40 the indicating means.

Figure 15 is an enlarged detail view showing 45 the connection between one of the shift keys and the shift mechanism.

Referring by numerals to the accompanying drawings, 10 indicates an accordion having a bellows section 11, a bass section 12, and a treble 50 section 14. The treble section is provided with a keyboard 15 on the front of which are mounted keys 16. The latter operate in the usual manner a suitable mechanism by means of which valves or clappers 17 open and close valve open- 55

ings 18 formed in a sound-board 19. This sound board is arranged in one end of the treble section 14.

This section 14 is box-shaped having side walls 20 and end walls 21, the sound board 19 being arranged to one side of said section 14 while the other side of said section is open and is connected to the corresponding end of the bellows 11.

The apertures 18 are arranged in a series of rows, as shown in Figure 3 and each row or group of apertures has arranged thereabove a corresponding tray 22, each of which is provided with a plurality of reeds (not shown). As shown in the drawings, there are five sets of trays, arranged parallel with each other, in said treble section 14. The inner trays 22a, 22b, and 22c are double, each containing two sets of reeds, while the outer ones are single and having each, one set of reeds. The trays are constructed in the usual manner and have reeds arranged in the side walls and having the lower ends open and fitting close against the inner face of the sound board 19 in such a manner as to enclose the corresponding row of apertures 18.

The inner trays 22a, 22b, and 22c are each provided with a slide plate or valve 24a, 24b, and 24c, respectively. These plates are slidably mounted in the bottom or lower end of each tray and each plate is provided with a plurality of apertures 25 which are so spaced that when the plate is in one position said apertures register with the corresponding row of apertures 18 and when said plate is moved in the opposite direction said apertures 25 are disposed with the corresponding apertures 18, thereby closing the communication between the trays and said apertures 18.

As stated before, there are four tone effects or changes that can be obtained in the instrument, namely, flute oboe, English horn bandonion, violin effect, and natural or accordion effect. In the instant case, two shift keys 26 and 27 are used. As shown in Figure 1, these shift keys are arranged parallel with each other immediately in front of the keys and are disposed above the gallery or cover 28 which is attached to the keyboard section 14 and encloses the clappers arranged therein. The shift keys are pivotally mounted at each end in blocks 29 which are fixed to the sound board 19. The keys or bars 26 and 27 have fixed to their undersides fingers or projections 30 and 31, respectively. Projection 30 bears against one end of an arm 32, the other end of which is fixed to or formed integral with a shaft 34. This shaft has bearing and extends through the keyboard 15 and receives on its opposite end an arm 35.

The downward extension or finger 31 of lever 27 engages one end of an arm 36, the opposite end of which is fixed to or formed integral with a shaft 37 which is revolvably mounted in and extends through the keyboard 15 and receives on its opposite end an arm 38. Arms 35 and 38 extend toward each other, as shown in Figure 2, and are spaced a suitable distance from each other. The inner end of arm 38 has pivotally connected thereto the lower end of a link 39 and the upper end of said link is pivotally connected to a sliding bar 40, as indicated at 41. This sliding bar is mounted on the rear side of keyboard 15 by means of screws 42 which engage longitudinal slots formed in said bar. A spring 44 has tendency to hold the bar 40 in outward position. The lower or inner end of said bar has pivotally connected

thereto, as indicated at 45, the upper or outer end of a tripper 46. A spring in the form of a spring wire 47 is fixed to bar 40 and extends longitudinally therefrom and engages at 48 said tripper 46, thereby yieldingly holding said tripper in longitudinal alignment with said bar 40.

The lower or inner end of tripper 46 is enlarged as indicated at 49 and is provided with a pair of transversely disposed downwardly presented shoulders 49a. This enlargement 49 overlaps the upper end of an oscillatable member 50 which is pivotally mounted at 51 to said keyboard 15 at a point which is longitudinally aligned with bar 40. This oscillatable member is of T-shape and has the ends of its cross bar 50a rebent, as indicated at 50b. These rebent portions are so arranged with respect to shoulders 49a that when said tripper 46 is moved downwardly one of said shoulders engages the corresponding rebent portion 50b and rocks said member 50. The lower end of oscillatable member 50 extends downwardly or inwardly past said keyboard 15 and terminates adjacent to one of the side walls 20 of the treble section 14. A rod 52 is fixed at one end to said end of member 50 and extends through a slot 54 formed in said wall 20 inwardly into the treble section 14, as shown in Figure 3.

Pivoted fixed to the inner end of bar 52 is one end of a rod 55. This rod extends longitudinally toward one end of said section and is pivotally connected to an arm 56 which extends downwardly from and is fixed to a horizontally and transversely disposed shaft 57. This shaft is journaled in bearings 58 which latter are mounted on a block 59 which is fixed to one of the end walls 21 and extends a suitable distance above the sound board 19. An arm 60 is fixed at its upper end to shaft 57 while the lower end of said arm engages an aperture formed in one end of slide plate 24b, which latter is slidably mounted in reed tray 22b.

Arm 58 which is fixed to shaft 57 and is operated by shift key 27 is connected by a link 58a to a bar 40a which operates, through a tripper 46a, oscillatable member 62 which is similar in shape and operation to member 50. The lower end of member 62 has fixed thereto a rod 64 which extends through a slot 65 in wall 20 into the treble section 14. The inner end of this rod 64 has pivotally fixed thereto a rod or connecting link 66. This rod is arranged parallel with rod 55 and is pivotally connected at its other end to an arm 67 which extends downwardly from and is fixed to a shaft 68. This shaft is disposed parallel with shaft 57 and is journaled in bearings 69. An arm 69 is fixed to shaft 68 and extends downwardly therefrom and engages an aperture formed in the plate or valve 24c which is slidably mounted in the reed tray 22c. Similarly, a rod or arm 71 is fixed to said shaft 68 on the opposite side of arm 60 and the lower end of said arm 71 engages an aperture formed in one end of the plate or slide valve 24a which is slidably mounted in the reed tray 22a.

In order to prevent escape of air through slots 54 and 65, a section of flexible material, such as thin leather 74, is cemented or glued along its edges to the inner face of wall 20. A leather washer 75 of suitable thickness is arranged on each rod 52 and 64 adjacent to the corresponding ends of connection rods 58 and 66. Member 74 is apertured at appropriate points and the edges of said apertures are cemented or glued to the respective washers 75 so as to provide an

air-tight seal. The flexible member 74 permits movement of bars 52 and 64 and at the same time forms a seal therefor.

An indicating means 76 is provided to enable the player to ascertain easily the positions of the slide plates 24a, 24b, and 24c. This indicating means is preferably located adjacent to the upper end wall 28a of cover or gallery 28, there being a window 77 formed in said end wall 10 through which said indicating means is visible. As shown, this means consists of a stationary chart 78 divided longitudinally into two zones 78a and 78b, each of which is divided into two sections. The sections of the upper zone 78b carry indicia "3" and "1" which corresponds, respectively, to the flute oboe and violin effect. The lower field 78 is marked "low octave" and the sections carry indicia "on" and "off".

A pointer 79 is mounted to operate over field 78a and is operated when the shift key 26 is depressed. A connecting link 80 is connected at one end, as at 81, to pointer 79 and at the other end to oscillatable member 50 as indicated at 82 so that said pointer is moved by and in accordance with the positioning of said member 50.

A pointer 84 is mounted to operate over zone 78b and has connected to it one end of a link 85 as indicated at 86, while the other end of said link is connected to oscillatable member 62 as indicated at 87.

A pad or cover 88 is secured to the underside or back of keyboard 15 and protects the mechanism mounted thereon. A lining 89 of felt or other suitable material is arranged on the inner 35 side of sound board 19 to provide a soft bed for receiving the reed trays and forming an air-tight seal therebetween and said sound board.

The shift keys 26 and 27 are arranged immediately back of the keys 16 so that they can be 40 easily operated by the tips of the player's fingers without requiring the player's hand to be removed from its normal playing position on the keyboard. By this arrangement of the shift keys, the tone effects of the accordion can be readily 45 changed without interrupting the playing of the accordion and the player can readily change from low octave to high octave and vice versa during the playing operation. The shift keys can be of any desired shape and size and they can 50 be arranged in a single row or otherwise spaced with respect to each other, the main object being to mount them adjacent to the keys and in such a manner that they can be easily operated.

The blocks 29 on which the shift keys are 55 mounted are arranged on the soundboard 19 in such a manner as not to interfere with the clappers 17 or their connections. The links 39 and 39a and their connections permit the operation of the mechanism mounted on the back of the 60 keyboard by means of said shift keys 26 and 27.

Springs 44 and 44a serve to restore members 40 and 40a, links 39 and 39a, and parts associated therewith, including shift keys 26 and 27, to normal positions after each operation. Members 50 and 62, plates 24a, 24b, and 24c, indicators 79 and 84, and their respective connections, remain in their last operative positions until the next operation.

Keys 26 and 27 and the shift mechanisms operated thereby are so arranged that they do not interfere either with the keys 16 and their operation, or the clapper mechanism actuated by said keys.

When all of the plates 24a, 24b, and 24c are 75 open, as in Figure 3, the accordion produces nat-

ural or accordion tone and the indicator 79 points to the legend "on" and indicator 84 to "3" (see Fig. 9).

To obtain violin effect, shift key 26 is actuated whereby the plate 24b is moved into closed 5 position. The reed tray 22b is now closed and only reed trays 22, 22a and 22c are active. The indicator 79 points to "off" while indicator 84 remains at "3".

In the English horn bandonion effect, shift key 10 27 is actuated to close plates 24a and 24c and shift key 28 is actuated (if plate 24b occupies closed position) to open plate 24b so that reed 15 trays 22 and 22b are active and reed trays 22a and 22c are closed or inactive. The indicator 19 points to "on" and indicator 84 points to "1".

When it is desired to obtain flute oboe effect, keys 26 and 27 are operated to close plates 24a, 24b, and 24c so that the reed trays 22a, 22b, and 22c are closed and only reed trays 22 are 20 active. Indicator 79 is at "off" and indicator 84 is at "1" position.

An important feature of the present invention is the fact that the player is able with a little practice to shift, without interruption, from the 25 low compass to the high octave while performing on the instrument. Thus a whole octave in the range of the keys is gained while playing up the scale and another octave is gained by going down the scale. All that the player is required 30 to do is to press key 26 to bring the pointer 79 to "on" position for low octave and to operate a shift key pivotally mounted on said sound board octave.

In the form shown in Figures 11 to 15, inclusive, a pair of shift mechanisms 90 for actuating the plates 24a, 24b and 24c is mounted on one of the side walls 20 of treble section 14. As in the previously described form the plates 24a and 24c are actuated simultaneously by one shift 40 mechanism while the plate 24b is actuated by the other shift mechanism.

In the present form, each mechanism 90 is simplified in construction and is reduced in size and condensed so that the two mechanisms can 45 be arranged in tandem longitudinally of the major axis of said wall, while in the previous form the mechanisms are arranged in parallel with each other and transversely of the keyboard.

Each shift mechanism 90 consists of a longitudinal 50 movable member 91 to one end of which is connected one end of a rock arm 92. This rock arm is fixed to a rock shaft 94 which is journaled transversely in the keyboard 15 and has mounted on its forward end an arm 95 operable 55 by a finger 96 of one of the shift keys 97.

Pivotedly mounted on the other end of member 91 is one end of a finger or tripper 98. This finger extends longitudinally from member 91 and is yieldably held in alignment therewith by 60 a spring wire 99 which latter also serves to restore the parts to normal positions after each operation.

Each finger 98 tapers outwardly and terminates adjacent to a V-shaped end 100 of an oscillatable or bell crank member 101. This member is pivotally mounted in one of the walls 20, as indicated at 102, and is provided at its end adjacent to said finger with a V-shaped notch 100a arranged to each side of said V-shaped end 100. 65 The other arm 104 of member 101 is disposed substantially transversely of the axis of the mechanism and has fixed thereto one end of a pin 105. This pin extends into section 14 through an arcuate slot 106 formed in side wall 20. The 70 75

inner end of pin 105 has connected thereto in one case one end of a connecting link 107 and in the other case one end of a connecting link 108. Said links 107 and 108 are connected to the 5 arms of the respective rock shafts 57 and 68 which in turn are operatively associated with sliding plates 24a, 24b, and 24c.

When one of the members 91 is actuated by the depression of the corresponding shift key, 10 the finger 96 carried by said member 91 is moved forwardly against the V-shaped end 100 and is deflected thereby to one side into one of the V-shaped notches 100a. Said member 101 is thus moved on its pivot 102 in appropriate direction, 15 thereby moving arm 104 from one position to another. This in turn actuates the connecting rod 107 or 108 as the case may be and the corresponding rock shaft 56 or 67 so that the corresponding plates 24a and 24c or plate 24b are 20 moved to open or close the respective reed trays in the same manner as hereinbefore described.

Each member 91 has a transverse extension 91a which terminates against the underside of the keyboard 15. A rod 109 connects one of the 25 extensions with an arm 110 which is fixed to one end of a rock shaft 111 and a rod 112 connects the other extension 91a with an arm 114 fixed to a sleeve 115. This sleeve is loosely mounted on shaft 111 and both are journaled in an aperture 30 formed in said keyboard. The other ends of said shaft 111 and sleeve 115 extend to the opposite or key side of the keyboard. An indicating chart 116 similar to chart 76 is arranged on this side of the keyboard and a window 117 is formed in the 35 end wall 28a of cover 28 to render said chart visible.

Each shift mechanism 90 is provided with a spring 91b, one end of which is anchored to the wall 20 and the other end of which is fixed to 40 member 91. This spring serves to restore the member 91 and parts connected thereto to normal position after each operation.

Fixed to the projecting end of sleeve 115 is a pointer 118 and fixed to the projecting end of 45 shaft 111 is a pointer 119. These pointers co-operate with the indicia on chart 116 to indicate the disposition of the various plates of the reed trays in the same manner as hereinbefore described. A cover 120 is attached to section 14 50 and the other side of keyboard 15 to enclose the shift mechanism and parts connected therewith.

I claim:

1. In an accordion, the combination with a 55 treble reed section, a keyboard including a plurality of keys, a plurality of reed trays, and a slide valve plate for each tray for shutting off and opening the same, of a shift key mounted on said treble reed section inwardly of said keys whereby said shift key can be operated by the finger tips 60 of the player's hand and a mechanism operable by said shift key and operatively associated with said slide valve plate for moving it at each operation of said shift key alternately into closed and open positions.

2. In an accordion, the combination with a 65 treble reed section having a sound board, a keyboard including a plurality of keys, a plurality of reed trays in said section, and a slide valve plate for each tray for shutting off and opening the same, of a shift key mounted on said sound board longitudinally of said accordion and inwardly of 70 said keys, a horizontally disposed rock shaft transversely mounted near one end of said reed section, a rock arm fixed at one end to said shaft 75 and having its opposite end engaging one end

of said slide plate, and a mechanism associated with said shift key and said shaft for alternately moving said slide plate into open and closed positions.

3. In an accordion, the combination with a 5 treble reed section having a sound board, a keyboard including a plurality of keys, a plurality of reed trays in said section, and a slide valve plate for each tray for shutting off and opening the same, of a shift key mounted on said sound board 10 and disposed inwardly of said keys whereby said shift key is adapted to be operated by the finger tips of the player's hand without removing said hand from its position on said keyboard, a horizontally disposed rock shaft transversely mounted 15 near one end of said reed section, a rock arm fixed at one end to said shaft and having its opposite end engaging one end of said slide plate, a mechanism associated with said shift key and said shaft for alternately moving said slide plate 20 into open and closed positions, and an indicating means operatively connected to said mechanism and operable thereby to indicate the position of said plate.

4. In an accordion of the character described, 25 the combination with a keyboard, a plurality of keys on said keyboard, a sound board provided with a plurality of openings, a plurality of reed trays arranged on said sound board, and a valve plate slidably mounted in each tray for opening 30 and closing the communication between said tray and the openings in said sound board, of a plurality of shift keys mounted on said sound board disposed thereabove inwardly of said keys, whereby said shift keys can be actuated by the 35 finger tips of the player's hand, a mechanism operable by each of said shift keys and connected to certain of said valve plates for moving the latter into and out of register with said openings.

5. A shift mechanism for accordions comprising in combination a reed section, a soundboard having a plurality of apertures closing one end of said section, a plurality of reed trays disposed in said reed section and enclosing said apertures, an apertured plate slidably mounted in certain 45 of said reed trays for opening and closing the communication between the tray and the corresponding apertures in said board, means for operating said plate, said means including a pin 50 extending through a slot in the wall of said reed section, a bell crank operatively mounted on the exterior of said wall and having one arm fixed to said pin and having the other arm formed with a V-shaped end having a notch at each side, a longitudinally movable member mounted on said 55 wall of said section, a finger pivotally mounted at one end on said member and having its other end terminating adjacent to said V-shaped end of said bell crank and adapted to be deflected into either notch for rocking said bell crank and 60 operating said plate, a shift key, and means connecting said shift key with said longitudinally movable member for operating the same.

6. A shift mechanism for accordions comprising in combination a reed section including a 65 soundboard having a plurality of apertures arranged in groups, a plurality of reed trays arranged in said section for enclosing said groups of apertures, an apertured plate slidably mounted in certain of said reed trays for opening and 70 closing communication between said trays and the corresponding groups of apertures, means in said reed section for operating said plates, said means including a pin extending outwardly from the wall of said section, a bell crank mounted ex- 75

teriorly on said wall and having a transverse arm secured to the outer end of said pin, the other arm of said bell crank being formed with a V-shaped end having a notch arranged at each side thereof, a longitudinally movable member mounted on said section and movable relatively to said bell crank, a finger pivotally mounted at one end on said movable member and having its other end presented toward the V-shaped end of said bell crank and adapted to enter either of said notches to rock said bell crank, a shift key, means connecting said shift key with said longitudinal member, and a spring for restoring said longitudinal members and parts associated therewith to 15 normal positions.

7. In a shift mechanism for accordions, a shift key, a longitudinally movable member, means connecting said shift key with said movable member and actuating the same, a finger pivotally mounted on said movable member, a bell crank pivotally mounted adjacent to said finger and having one arm disposed longitudinally and formed with a V-shaped end provided with a notch at each side, said finger being movable by 20 said longitudinal member toward said bell crank and being adapted to be deflected by said V-shaped end into one of said notches, thereby rocking said bell crank, a reed tray, an apertured plate slidably mounted in said tray, and connections between said plate and said bell crank for 25 actuating said plate upon each operation of said shift key.

8. In a shift mechanism for accordions, the combination of a reed section, a reed tray mounted therein, an apertured plate slidably mounted in said reed tray for opening and closing communication therewith, a bell crank pivotally mounted on said reed section and having one arm disposed longitudinally thereof and the other 30 arm transversely, means connecting said plate with said transverse arm, a longitudinally movable shift member mounted on said reed section, a finger pivotally mounted at one end on said shift member and having its other end adapted 35 to engage said longitudinal arm to either side of the longitudinal axis thereof, thereby rocking said bell crank from one extreme position to the other, a spring for yieldably holding said finger in longitudinal position, a shift key for actuating 40 said shift member, and means for restoring said shift member and parts associated therewith to their normal positions.

9. In an accordion of the character described, the combination with a reed section, a sound 45 board having a plurality of apertures closing one end of said section, reed trays disposed in said reed section and enclosing said apertures, and an apertured plate slidably mounted in each reed tray for opening and closing the communication 50 between said tray and said board apertures, of a rock arm mounted in said reed sections and having one end operatively engaging one end of said plate, means located on one of the side walls of said reed section for actuating said rock arm,

a rock shaft, an arm fixed at one end to the inner end of said shaft and having its opposite end connected to said means for actuating the same, another arm fixed to the outer end of said shaft, a shift key pivotally mounted on said sound board 5 and disposed inwardly of said key board for depressing said last mentioned arm and actuating said rock shaft and parts associated therewith.

10. In an accordion of the character described, the combination with a keyboard, a reed section, 10 a sound board having a plurality of apertures enclosing one end of said section, a reed tray disposed in said reed section and enclosing said apertures, and a plate slidably mounted in said reed tray for opening and closing the communication 15 between said tray and said board apertures, of a rock arm pivotally mounted in said reed section and having one end operatively engaging said plate, means located on one of the side walls of said reed section and operatively connected to said rock arm, a rock shaft journaled transversely in said key board near said reed section side wall, an arm fixed to the inner end of said shaft and operatively engaging said means, another arm fixed to the outer end of 20 said shaft, and a shift key disposed longitudinally 25 above said sound board inwardly of said key-board for actuating said outer arm.

11. In an accordion of the class described, the combination with a keyboard, a reed section, and 30 a sound board closing one end of said reed section, of a reed tray in said section, a slidable plate for controlling said reed tray, means in said reed section for operating said plate, said means including a pin extending outwardly through a slot 35 in one of the side walls of said reed section, an oscillatable member mounted exteriorly on said slotted side wall and having one end fixed to the projecting end of said pin, a reciprocable member mounted on said slotted reed section side wall 40 and adapted to engage said oscillatable member and move it alternately in opposite directions, a rock shaft journaled transversely in said sound board and having one end operatively connected 45 to said reciprocable member, an arm fixed on the opposite end of said shaft, and a shift key operatively mounted on said sound board and adapted to engage said last mentioned arm and actuate said shaft and parts associated therewith.

12. In an accordion of the character described, 50 a shift key mechanism comprising a depressible shift key bar disposed longitudinally of the accordion, a rock shaft disposed below and transversely of said key, an arm fixed to one end of said shaft and operable by said shift key, a second arm fixed to the other end of said shaft, a longitudinally movable member operable by said second arm, and means actuated by said longitudinally movable member and operatively associated with a slide plate of a reed section for 55 operating said plate alternately in opposite directions at each depression of said shift key bar.

MAX B. LUTTBEG.
